(57) **CLAIM**

The ornamental design for a tow hitch safety cover, as shown and described.

DESCRIPTION

FIG. 1 is a perspective view of a tow hitch safety cover, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The crosshatching pattern shown in FIGS. 1, 3, 5, and 6 represent hook and loop fasteners.
